UNITED STATES PATENT OFFICE.

CHARLES WAGNER, OF GRANTWOOD, AND AUGUST HORMEL, OF JERSEY CITY, NEW JERSEY, ASSIGNEES TO CHARLES WAGNER LITHO. MACHINERY COMPANY, INC., A CORPORATION OF NEW YORK.

COATING MACHINE.

Application filed February 18, 1924. Serial No. 693,503.

This invention relates to improvements in coating machines.

One of the objects of this invention is to produce a coating machine provided with a rotatably supported or mounted coating roller having a plurality of coating surfaces or areas separated and preferably completely isolated by transverse and circumferential non-coating grooves or channels, combined with means adapted to feed sheets or plates of metal or other material to be coated into proper registration with such separated coating areas.

Another object of this invention is to produce a machine embodying a coating roller having coating areas separated by non-coating transverse grooves and means for rotating said roller, and positive feeding means having the movement of its feeding element synchronized with the movement of the roller to cause proper registration of the plates with the boundaries of the areas comprising the non-coating and separating transverse grooves in the roller.

Another object of the invention is to utilize, in combination with a coating roller, side aligning means adapted to engage the side edges of plates of material to be coated to cause the same to be moved into alignment with the boundaries of the areas defined by the circumferential non-coating and separating grooves in the roller.

Another object of our invention is to produce a machine embodying a rotatably supported coating roller having a series of coating areas bounded by non-coating rectilinear grooves extending transversely and circumferentially, and means for rotating said roller, of plate-feeding means synchronized with the roller-rotating means to cause registration with the non-coating transverse grooves and side aligning elements to cause registration with the non-coating circumferential grooves.

Another object of this invention is to provide in a machine of the character described having a coating roller provided with a series of separated coating areas, means for facilitating the scraping of the plate-supporting roller or drum, and to this end we preferably utilize a spreading roller for initially spreading the coating material over the uncoated strips on the supporting roller or drum to enable the scraper more ef-

fectively to remove the film of coating material particularly adjacent to the area-separating lines transferred from the coating roller.

Another object of this invention is to provide improved means for distributing the coating liquid to prevent the accumulation of material in the pocket or groove formed between the abutting peripheries of the coating roller and the distributing roller, and to this end we arrange between the two lines of contact of said distributing roller with the supply and coating rollers respectively an additional squeeze-off roller which engages said distributing roller and squeezes off any excess of material before the same reaches the abutting periphery of the coating roller.

Another object of this invention is to provide improved lever-operated means for first lowering the supporting roller to separate the same from the coating roller and then in the same continuous cycle of movement or operation lowering the coating roller to separate the same from the distributing rollers while maintaining separation of the coating roller from the supporting roller.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a vertical section of a coating machine embodying my invention, the section being taken on the line 1—1 of Fig. 2;

Fig. 2 is a cross-section of the machine shown in Fig. 1 on the line 2—2 of said Fig. 1;

Fig. 3 is a fragmentary section on the line 3—3 of Fig. 2 showing the coating and supporting rollers in side elevation;

Fig. 4 is a fragmentary section through the feeding table on the line 4—4 of Fig. 2;

Fig. 5 is a fragmentary section on the line 5—5 of Fig. 2 looking in the direction of the arrow and showing the coating roller in operative position in contact with the supporting and distributing rollers respectively; and

Fig. 6 is a view similar to Fig. 5 showing the inoperative position and separation of the coating, supporting and distributing rollers respectively.

- 5 Referring now to these drawings, which illustrate a preferred embodiment of my invention, 1 indicates frame supporting members of conventional form which are tied together in any suitable manner. Rotatably mounted in the supporting frame members 1 by means of the usual pairs of slidable bearing blocks 2 and 3 are a coating roller 4 and a supporting roller 5, the bearing blocks 2 being pressed upwardly by springs 16 2^a and adjusted by screws 2^b.

The frame members 1 are also provided with brackets 1^a on which is supported in alignment with the meeting peripheries of the supporting and coating rollers a table 20^b top 6 stiffened at its outer end by means of an angle iron 6^a and at its inner end by a strip 6^b, the table top in the embodiment shown comprising as shown three metal plates and being connected to the bracket 25^c by screws 6^c.

The table top 6 is preferably provided intermediate its side edges with a pair of slots 7 and supported beneath the table in alignment with these slots 7 are a pair of conveyor chains 8 having a plurality, and preferably, as shown, two pairs of feeding elements 8^a, which during a part of the travel of the conveyor chains on their upper stretches project upwardly through the slots 7, the chain being preferably so mounted and guided that the fingers at the beginning of the feeding movement project up the full distance and toward the end of the feeding movement are lowered out of the slot until finally they extend entirely below the same. As shown, the chains are guided by running over supporting channels 8^b for portions of their upper stretches. These channels guide the chains and maintain the feeding elements in proper position above the table top or feed-bed during the major portion of the feeding movement thereof, after which, due to the lower mounting of the inner end of the chain, the feeding elements in passing through the slots gradually disappear below the level of the table.

In the preferred embodiment of our invention, the periphery of the coating roller 4 is split up by a series of transverse and circumferential grooves into a series of separated and preferably completely isolated coating areas, so that a single metal plate, or other sheet of material fed through the machine, will be provided with a series of 60 coated portions or areas separated or bounded at sides and ends by uncoated marginal strips, the coated areas forming blanks which may be severed from the plates or sheets to provide coated units or blanks having uncoated marginal strips which will en-

able ready soldering of the margins without scraping. The movement of the conveyor chains 8 and their feeding fingers 8^a are preferably synchronized with the rotation of the coating roller to cause the edges 70 of the sheet to register with the non-coating transverse grooves or channels in the roller.

In order to have the side edges of the plates register with the circumferential channels, it is desirable to provide side-aligning elements, and in the preferred form illustrated we provide a pair of spring-pressed aligning elements 9 mounted upon carrying rods 10—10^a slidable in bearings 1^b in the bracket 1^a. These carrying rods 80

10-10* are connected by rods 11 to opposite ends of a centrally located pivoted rocking link 12 so that said rods and the aligning elements will be caused to move simultaneously toward and away from each other. 83

Movement is preferably transmitted to said rods and elements by connecting the end of one of the rods with a cam slot 13 in a roller 14. As shown, the end of the rod 10* is connected by a slot and pin connection with

an arm 15^a of a bell-crank lever 15 pivoted intermediate its ends at 15^b on the bracket 1^a, the other arm 15^c of said bell-crank lever being provided with a roller 16 fitted within the cam-groove 13 of the roller 14. Move-

ment may be transmitted to this cam roller in any suitable manner and as shown is rotated, and preferably synchronized with the movement of the feeding elements, by one of a series of gears hereinafter specified.

Obviously when the cam roller is rotated the bell crank lever will be rocked about its pivotal point 15^b and this will cause the simultaneous movement in opposite directions of the rods 10 and 10^a carrying the spring. 10

pressed aligning elements. As illustrated, these elements are mounted upon brackets 9^a which are adjustable on the respective carrying rods 10—10^a. As more particularly illustrated in Fig. 4, each element is mounted upon a pair of pins 9^b having

mounted upon a pair of pins 5 having springs 9^c interposed between the same and the brackets 9^a. Obviously when movement is imparted to the cam slot in synchronization with the conveyer chain, as aforesaid, these aligning elements will move inwardly

these aligning elements will move inwardly toward each other to engage the plate being fed to the machine and if the same is out of alignment on either side, the element on that side will engage the edge thereof and cause the said plate, as it is finally

11
moved into contact with the coating and supporting rollers, to assume a position or relationship that the edges of the plate or sheet will be in registration or parallelism with the circumferential grooves in the roll-

er. It will also be apparent that the combined action of the aligning elements and the feeding elements will cause proper registration of the plate or sheet with both the 13

transverse and circumferential grooves in the roller. Thus the front and back edges of the plate will be in registration with one of the transverse grooves in the said roller and side edges will register with the circumferential grooves. Blanks or coated units may thus be formed having their edges registering with the edges of the sheet to avoid loss of material and when such blanks are severed along the uncoated strips formed by the grooves in the roller, uncoated margins are formed which facilitate soldering of such edges. In many cases also the sheet fed into the machine contains a series of printed legends or labels and the alignment and feed fingers as above specified will cause such printed legends to come within and register with the separated coating areas on the roller. This is particularly true where the blanks are intended for use in making cans or like containers.

Our distributing apparatus for the coating liquid preferably embodies the conventional tank 17 with a supply roller 18 rotatably mounted in contact with the liquid therein, and a distributing roller 19 rotatably mounted in contact with the coating roller 4. These rollers are mounted in conventional manner on a bracket extending from the frame 1 at the upper end thereof, and a groove, crevice or pocket is necessarily formed between the coating roller and the distributing roller. With many forms of coating material an excessive accumulation thereof occurs in the pocket or groove so formed and this results in uneven or rough coating of the plates. In order to prevent this excessive accumulation of material, we preferably mount in any suitable manner an additional roller having its periphery in contact with the distributing roller at a plane or line between the lines of contact of said roller with the coating and supply rollers respectively, so as to squeeze off said distributing roller, before it reaches said crevice, groove or pocket, any excess of material that would otherwise pass to the coating roller and as shown, a squeeze-off roller 20 is so rotatably mounted in contact with the said distributing roller as to squeeze off any excessive material which may be carried by said roller. By this arrangement we are enabled to more evenly distribute coating on the coating roller and on the plates or sheets of metal or other material coated thereby.

Our improved means for scraping of the supporting roller will now be described. It comprises the use in combination with a conventional holder 26 for a scraper blade 27 which holder is mounted on the shaft 24 supported on a bracket 3^a carried by the bearing blocks 3 of the supporting roller. Said blade 27 is normally held in contact with the periphery of the supporting roller

5 by conventional means so as to scrape therefrom coating material which accumulates thereon. In a machine having a roller with the series of isolated or separated areas hereinabove described, the supporting roller 70 will naturally become coated with a series of isolated areas separated from each other by uncoated strips and we have found that a scraper of the type hereinabove described will not effectively scrape each of such isolated coatings from the periphery of said supporting roller. We have therefore provided means for spreading and connecting the isolated or separated sections or areas to form a single layer or coat which may thereafter be removed in a substantially single sheet or layer by the scraper. For this purpose, we pivot intermediate their ends on shaft 25 also supported in brackets 3^a, arms 28 which carry at one end a pressure roller 85 29 normally forced into contact with the periphery of the supporting roller by screws 30 mounted in a block 30^a on a rod 31 and engaging the opposite ends of said arms 28. The scraper is likewise forced into contact 90 with the periphery of the roller by providing the holder with outward extensions 27^a, which are pressed downwardly by screws 27^b mounted in blocks 27^c on the rod 31. Our preferred means for separating the rollers embodies means for lowering the supporting roller and its auxiliary scraper and spreading rollers and by the same cycle of operation or movement lowering the coating roller away from the distributing roller 95 100 while at the same time maintaining a separation between the coating and supporting rollers and also between the latter and its auxiliary scraper and spreading roller, and to this end we utilize the conventional operating lever 21 fixed on a rock shaft 21^a adapted upon movement of the lever to turn the rock arms 22 connected by turnbuckle links 23 to the bearing blocks 3 of the supporting roller. The spreader-roller and 105 scraper being, as aforesaid, mounted on the bearing-block 3 will move with said bearing block when the same is lowered through operation of the lever 21 but by reason of the contact of the arms and members 28 and 27^a with their respective screws will, upon lowering of said block, be separated from the periphery of said roller 5. In the preferred embodiment illustrated our means for lowering the coating roller and separating 110 115 the same from the distributing roller after the supporting roller has been separated from such coating roller, comprises the provision on the rock shaft 21^a of a pair of cams 32 having a projection 32^a which, upon rocking of the rock shaft 21^a by the lever 21 will contact with pedals 33 suitably pivoted on the frame and having, as shown, a connection intermediate its ends at 33^a with upright rods 34, which have at their upper 120 125 ends a connection with the arms 28 and 27^a respectively.

end hooks 34^a connected to pins 35 on the bearing blocks 2 of the contact roller. The lever 21, in the embodiment shown, has intermediate its ends a slot 21^b which contacts 5 with a pin 21^c on the frame 1 so as to limit the movement of said lever 21. Obviously the upward movement of the lever 21 will first cause a lowering of the bearing blocks for the supporting rollers and a continuance 10 of its cycle of movement will thereafter, through the action of the cam 32 on the pedal 33, cause a lowering of the blocks 2 to separate the coating roller from the distributing roller, it being understood that the parts 15 and movements will be so proportioned that the supporting roller will in its lowermost position be still separated from the contact roller when the same is in its lowermost position. We preferably mount at the opposite 20 side of the contact rollers a series of take-off belts 36 which, as shown, are mounted on roller 37 fast on a shaft 38 driven by gears 38^a—38^b.

In order effectively to drive the various 25 rollers, belts and feed mechanism and to synchronize the movement of the feeding elements with the rollers and also to synchronize the movement of the cam-operated aligning elements with the feeding elements, 30 we preferably provide drive pulleys 39 mounted on a drive shaft 40 having a gear 41 which meshes with a gear 42 mounted on a shaft 43, on which the supporting roller 5 is mounted. Said shaft 43 has fixed thereon 35 at its opposite end a gear 44 which, in the preferred embodiment shown, meshes with an idler 45 on the drive-shaft 40, which meshes with a double toothed idler 46 on the stud shaft 47. This idler gear 46 meshes 40 with a gear 48 on a shaft 49, upon which the coating roller 4 is mounted. Said gear 48 meshes with a gear 50 on the shaft 51, on which the distributing roller 19 is mounted. The gear 50 meshes with the gears 52 on the 45 shaft 53, on which the supply roller 18 is mounted and said gear 50 also meshes with a gear 54 on a shaft 55 on which the squeeze-off roller 20 is mounted. The gear 44 also meshes with a gear 56 which is mounted on 50 the stud shaft 57, on which the cam-drum 14 is mounted, and the gear 56 in turn meshes with pinion 58 on the shaft 59 which extends beneath the table and has mounted thereon drive sprockets 60 which drive the conveyor 55 chains 8 over sprockets 61 mounted on shaft 62 supported in bearing brackets 62^a on the lower surface of the table top 6.

Having described our invention, we claim:—

60 1. A coating machine embodying, in combination, a coating-roller having a plurality of coating areas separated by non-coating grooves, a supporting-roller rotatably mounted below and adapted to bring plates

of material to be coated into contact with the coating-roller, means for applying coating material to said roller, means for feeding plates between said rollers, a scraper in contact with the periphery of said supporting-roller and means for spreading the material on said supporting-roller to facilitate the removal thereof by the scraper. 65 70

2. A coating machine embodying, in combination, a coating-roller having a plurality of coating areas separated by non-coating 75 grooves, a supporting-roller rotatably mounted below the same and adapted to move plates of material to be coated into contact therewith, means for applying coating material to said roller, means for feeding plates between said roller, a scraper in contact with the periphery of said supporting-roller, and a spreader-roller in contact with said supporting-roller for spreading the coating material on said supporting- 80 85 roller to facilitate the removal thereof by the scraper. 85

3. A coating machine embodying, in combination, a coating-roller, means for rotatably supporting said roller, means for rotating said roller and distributing apparatus comprising a supply tank, a supply-roller having its periphery rotating in contact with the material in said tank, a distributing-roller rotatably mounted and contacting 90 with said supply-roller and with the coating-roller, and a squeeze-off roller rotatably mounted in contact with said distributing-roller to prevent the excessive accumulation 95 of material in the pocket formed between the distributing-roller and the coating-roller. 100

4. A coating machine embodying, in combination, a coating-roller, a plate-supporting roller rotatably mounted below the same and in contact therewith, a distributing-roller mounted above the axis of said coating-roller and contacting with the periphery thereof and mechanism movable to separate said supporting-roller from said coating-roller and in the same continuous cycle of movement to separate the coating-roller 105 from the distributing-roller. 110

5. A coating machine embodying, in combination, a coating-roller, a plate-supporting roller rotatably mounted below the same and in contact therewith, a distributing-roller mounted above the axis of said coating-roller and contacting with the periphery thereof and lever-mechanism movable to separate said supporting-roller from said coating-roller and a cam, actuated by the movement of said operating lever, for lowering the coating-roller to separate the same 115 from the distributing-roller. 120

In witness whereof, we have signed our 125 names to the foregoing specification.

CHARLES WAGNER.
AUGUST HORMEL.
